UNITED STATES PATENT OFFICE

JOSEPH KERKHOFF, OF ATTLEBORO, MASSACHUSETTS, ASSIGNOR TO F. L. TORREY & COMPANY, A COPARTNERSHIP COMPOSED OF FRED L. TORREY AND JOSEPH KERKHOFF, BOTH OF ATTLEBORO, MASSACHUSETTS, DOING BUSINESS AT ATTLEBORO, MASSACHUSETTS

INSIGNIA ATTACHMENT

Application filed February 8, 1929. Serial No. 338,397.

This invention relates to a character designated or initialed article; and has for its object to provide a construction by which two sheet metal parts may be removably attached together by suitably shaping the parts and without the necessity of providing any additional support or separate member for such attachment.

A further object of the invention is to form an insignia plate or element which will cooperate with formations in a face plate to releasably and positively secure the insignia plate to the face plate in a manner which can readily be removed and replaced by a similarly formed insignia plate when desired.

With these and other objects in view, the invention consists of certain novel features of construction, as will be more fully described, and particularly pointed out in the appended claims.

In the accompanying drawings:

Fig. 1 is a top plan view of a portion of a belt with a buckle mounted thereon showing the insignia in the form of a letter mounted on the face of the buckle.

Fig. 2 is a section on line 2—2 of Fig. 1.

Fig. 3 is a section similar to Fig. 1 and showing the insignia removed.

Fig. 4 is a top plan view of the buckle with the insignia removed.

Fig. 5 is a top plan view of the insignia element.

Fig. 6 is an enlarged sectional view of the detail of the plate showing the insignia mounted therein.

In many forms of jewelry work as well as in other arts, it is desirable to provide individualistic articles by having an initial letter or an emblem in a conspicuous position upon the article and in order that a simple and inexpensive construction may be provided for removably securing a sheet metal insignia carrying plate to the sheet metal face plate of a desired article such as a belt buckle or the like, for which it is particularly adapted, I have provided two spaced slots in the sheet stock of the face plate of the buckle or other like object and provided a sheet metal insignia element with

fingers extending therefrom to be positioned in the slots formed in the plate, the fingers being such that one extends through the slot and over the back surface of the face plate and the other being shaped to resiliently engage the edge of the slot through which it is snapped to hold the insignia element in position. I have also found it desirable to recess a portion of the face plate to receive the insignia so that it may lie flush with the face plate of the buckle and the following is a detailed description of the present embodiment of this invention and illustrating the preferred means by which these advantageous results may be accomplished.

While I have illustrated this invention as applied to a belt buckle, it will be readily apparent that many sheet metal objects are equally adapted to receive and have mounted thereon insignia, and I therefore desire that it be understood that although I refer particularly to a buckle, other objects of a similar construction are within the scope of this invention.

With reference to the drawings, 10 designates one part and 11 another part of the belt which may be suitably secured together by a buckle 12, formed of sheet stock having a face plate 13 with surface 14 which is depressed as at 15 in a suitable shape such as 80 octagonal as herein shown to receive the separate element or plate 16 having insignia 17 such as a letter or emblem inscribed or mounted on its surface.

The recess or depressed portion 15 is provided with a pair of slots 18 and 19 located adjacent its edge or junction thereof with the surface of the plate. The element 16 is provided with a finger 20 offset as at 21 to extend through the opening 18 and overlie a portion of the back surface of the plate to prevent withdrawal of the element in a direction at right angles to the surface of the plate, and on the diametrically opposite side of the insignia element a finger 22 is rolled, as illustrated in Figs. 2 and 6, to form a resilient knob to engage the edge 23 of the stock about the slot 19 and frictionally retain the element 16 in its recess 15 in the plate 13.

The sheet stock of the element 16 is of a

100

thickness substantially the same as the depth of the recess 13 from the surface 14, so that when the element 16 is mounted in this depression the outer surface of the insignia element and the surface 14 of the plate are in substantially the same plane and conform to the general appearance of the buckle.

It will be understood that the resiliency of the knob 22 tends to force the finger 20 firmly against the edge wall 24 of the material surrounding the slot 18 and prevents the removal of the insignia element except by first forcing the knob 22 outwardly from the back surface of the plate whereby it may be swung in a hinging fashion to a position to withdraw the finger 20 from its slot 18 and completely remove the insignia element 16 from position after which an insignia element having a different inscription thereon such as a different letter may be substituted so that a retail merchant need carry only a few buckles accompanied by a plurality of different insignia or letters to supply his trade with buckles having different letters or emblematical symbols thereon.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a device of the character described, a face plate having spaced slots therein, an element having insignia thereon, integral fingers extending from said element, one offset from the plane of said element of a size to extend through one of said slots and engage the surrounding stock and the other finger folded into a coil to form a resilient knob to resiliently engage the stock surrounding the other slot and retain the element in position.
2. In a belt buckle, a face plate having a depression therein with spaced slots in the depressed portion and a separate element having insignia thereon of a size to fit said depression, an offset finger on said element to extend through one of said slots and engage an edge and overlie the back of the stock surrounding said slot, and a second finger on said element rolled to provide a resilient knob of a size and shape to extend through the other of said slots and resiliently and frictionally engage the edge of the stock thereabout whereby said element is removably secured in said depression.
3. In a belt buckle a face plate having a surface with a depression therein with spaced slots in the depressed portion along the junction of the depressed portion with the surface of the plate, and a separate element having insignia thereon of a size and shape to fit said depression and substantially

the thickness thereof, an offset finger on said element to extend through one of said slots and engage an edge and overlie the back of the stock surrounding said slot, and a second finger on said element rolled to provide a resilient knob of a size and shape to extend through the other of said slots and resiliently and frictionally engage the edge of the stock thereabout whereby said element is removably secured in said depression substantially flush with the surface of said plate.

In testimony whereof I affix my signature.
JOSEPH KERKHOFF.
